[57] ABSTRACT

A tool for cold pressure welding workpieces such as coaxial cables together. The tool has a compact arrangement so that it may be hand held and operated. A hydraulic pump and motor are incorporated for providing a force amplification which lends to the compactness and light weight of the assembly. The hydraulic motor operates pairs of dies which first grip the ends of the workpieces to be welded and then force these ends into engagement to achieve a cold pressure weld. The pump is constructed so as to effect rapid initial movement of the dies and subsequent slower movement with a greater force amplification. A pressure relief valve is interposed in the hydraulic circuit for limiting the force applied to the dies. The dies are held in pivotally supported parts of the tool so that the tool may be conveniently opened for inspection, replacement or cleaning of the dies.

HYDRAULICALLY OPERATED BUTT WELDER

CROSS REFERENCE TO RELATED APPLICATION

This application is a continuation-in-part of our earlier application entitled "Cable Welding Tool," Ser. No. 217,096, filed Jan. 12, 1972 now Patent No. 3,800,997.

BACKGROUND OF THE INVENTION

This invention relates to an improved hydraulically operated pressure welding apparatus and to an improved pump for such an apparatus.

In our aforesaid, copending patent application there is disclosed a cold pressure welding tool having a manually operated hydraulic pump for generating the welding forces. As is noted in that application, the use of the hydraulic pump permits a compact assembly while still exerting extremely high mechanical pressure. However, the mechanical advantage afforded by the pump is achieved at a sacrifice in rate of die closure. That is, the operating handle must be pumped a number of times to move the dies from their opened positions to their welding positions. The disadvantage of such a construction, in certain applications, are believed to be apparent.

It is, therefore, a principal object of the invention to provide an improved hydraulically operated cold pressure welding apparatus.

It is another object of the invention to provide a hydraulically operated cold pressure welding apparatus having an improved hydraulic pump.

It is a further object of the invention to provide a hydraulically operated cold pressure welding apparatus embodying a two-stage pump that effects a rapid initial rate of closure of the dies and a subsequent slower rate of closure.

In a substantial number of cold welding mechanisms a die set is used that is moved between an opened position and a welding position. It is particularly advantageous in connection with such a mechanism if the initial movement of the dies toward their welding position can be accomplished at a high rate of speed. The final degree of closure, however, accomplishes the upset of the piece to be welded and should be accomplished with the exertion of extremely high pressures. Mechanisms that achieve high rates of speed will, particularly if mechanically operated, provide very low force amplification.

It is, therefore, another object of this invention to provide a variable rate force amplification device for use in a cold pressure welding apparatus.

SUMMARY OF THE INVENTION

A first feature of this invention is adapted to be embodied in a cold welding apparatus comprising die means movable between an opened position and a welding position for upsetting a work piece and operating means for moving the die means between their opened position and their welding position. In such an apparatus the invention comprises providing means in the operating means for effecting initial movement of the die means from its opened position to its closed position at a rapid rate and for thereafter effecting movement of the die means to their closed position at a slower rate.

Another feature of the invention is adapted to be embodied in a cold welding apparatus of the type described in the immediately preceding paragraph. In such an embodiment the improvement comprises providing means in the operating means for effecting rapid movement of the die means from its opened position to its closed position with a relatively low rate of force amplification. Subsequent movement of the die means is accomplished at a considerably higher ratio of mechanical advantage.

Yet another feature of the invention is adapted to be embodied in a pump that is particularly adapted for use in a hydraulically operated cold welding apparatus. The pump comprises first and second pistons the second of which has a considerably larger area than the first. Each piston is slidably received in a respective cylinder bore for displacing fluid in response to its movement. An operative connection is provided between the pistons for moving them together so that each piston will displace fluid until a predetermined pressure is reached. At this point, the operative connection permits relative movement between the pistons so that the second piston will no longer displace fluid and so that the first piston will then displace fluid at a higher pressure.

BRIEF DESCRIPTION OF THE DRAWINGS

FIG. 1 is a perspective view of a cold welding tool embodying this invention.

FIG. 2 is an enlarged longitudinal cross sectional view of the tool shown in FIG. 1.

FIG. 3 is a cross sectional view taken along the line 3-3 of FIG. 2.

FIG. 4 is a cross sectional view taken along the line 4-4 of FIG. 2.

FIG. 5 is an enlarged view taken generally in the direction of the line 5-5 of FIG. 2.

FIG. 6 is a view taken in the direction of the line 6-6 in FIG. 5 with the dies removed to more clearly show the construction.

FIG. 7 is a view taken in the direction of the line 7-7 in FIG. 5 with the dies removed to more clearly show the construction.

DESCRIPTION OF THE PREFERRED EMBODIMENT

A cold pressure welding tool embodying this invention is identified generally by the reference numeral 11. The tool is, as will become more apparent as this description proceeds, relatively light in weight and yet is capable of exerting extremely high welding pressures. Because of these characteristics, the tool 11 is particularly adapted for hand operation and is useful in the welding of coaxial cables. This latter welding operation may be performed at the top of a utility pole.

The tool 11 is comprised of a main body assembly or housing 12. A handle 13 is pivotally supported at one end of the housing assembly by means of a pivot pin 14 that is held in place axially by snap rings 15. As will become more apparent, the handle 13 when pivoted operates a two stage hydraulic pump 16 which, in turn, feeds pressurized hydraulic fluid to a fluid motor 17 for effecting welding operation of the die set 18. Thus, a hydraulic force amplification of a variable or two stage rate is provided between the handle 13 and the die set 18.

The housing assembly 12 is comprised of a pair of generally cylindrically shaped housing members 19 and 21. The housing member 21 is formed with a boss 22 that is nested between a pair of bosses 23 and 24 of the housing member 19 (FIG. 4). The housing member bosses 22, 23 and 24 are formed with aligned bores 25, 26 and 27, respectively. A pin 28 extends through the bores 25, 26 and 27 to pivotally connect the housing members 19 and 21 together. Snap rings 29 and 31 are received on opposite ends of the pin 28 to axially locate the pin.

The housing members 19 and 21 are held in a closed position (as shown in Figures of the drawings) by a latch mechanism, indicated generally by the reference numeral 32. The latch mechanism 32 includes a latching member 33 that is pivotally supported between a pair of outwardly extending arms 34 and 35 of the housing member 19. This pivotal support is provided by means of a pivot pin 36 that extends through a bore 37 in the latching member 33 and through corresponding bores in the arms 34 and 35. The pivot pin 36 is held axially in place by snap rings 38.

The latching member 33 is pivotable between a latched position as shown in the drawings and a released position. In the latched position the latching member 33 engages a shoulder 39 formed on an extending portion 41 of the housing member 21. This engagement retains the members 19 and 21 in their closed position. If it is desired to open the housing members 19 and 21, for a reason which will become more apparent as this description proceeds, the latching member 33 is pivoted to a released position free of the shoulder 39. The housing member 19 may then be pivoted relative to the housing member 21 about the pivot pin 28. A dowel 42 extends through a bore in the housing member portion 22 and is engaged by the portions 23 and 24 of the housing member 19 to limit the degree of opening movement.

The housing assembly 12 further includes a pump housing 43 that is spaced from the housing member 21. A pair of sheet metal stiffeners 44 and 45 are held together by socket headed screws 46 and span the area from the pump housing 43 to the housing member 21. The stiffeners 44 and 45 aid in connecting the pump housing 43 to the housing member 21.

The two stage pump includes a first bore 47 formed in the pump housing 43 and extending generally perpendicularly to the axis of the handle pivot pin 14. The bore 47 does not, however, intersect this axis. A smaller diameter bore 48 is formed concentrically with the bore 47 at the lower end of the bore 47. An inner piston 49 extends through the bore 47 and is slidably supported in the bore 48. Adjacent the outer end of the piston 49 a seal 50 is positioned in the bore 47 which sealingly engages the piston 49. The upper end of the piston 49 is formed with an enlarged lug 51. This lug 51 extends through a central opening in the handle assembly 13 adjacent the pivot pin 14. A pivot pin 52 extends through a bore in the lug 51 and through respective openings formed in the handle assembly 13. It should be noted therefore that pivotal movement of the handle assembly 13 about the pivot pin 14 will cause reciprocation of the piston 49 in the bore 48.

An outer piston 53 is formed at a bore 54 to slidably support the outer piston 53 on the inner piston 49. The outer diameter of the outer piston 53 is slidably supported in the bore 47. The lower end of the piston 53

is threaded, at 55, to receive a piston head 56 which is also slidable in the bore 47. A seal 57 is compressed between the piston 53 and the piston head 56 to effect a seal at the bore 47.

The upper end of the outer piston 53 extends through the aforescribed opening in the handle 13 and is bifurcated to encompass the lug 51. Elongated slots 58 are formed in the bifurcated portion of the piston 53 and slidably receive the pivot pin 52 to effect a lost motion connection between the handle 13 and the piston 53 for a reason which will become apparent. A spring 59 is contained between the inner piston 49 and the piston head 56 and acts against a shoulder on the inner piston 49 so as to urge the outer piston 53 downwardly relative to the inner piston 49.

A bore 60 intersects the bore 47 adjacent the seal 50. The bore 60 is, in turn, intersected by a bore 61 that extends perpendicularly to the bore 60 and parallel to the bore 47. A check valve 62 is supported within the bore 61 for controlling the flow from the bore 60 into the bore 61, as will become apparent.

A bore 63 intersects the bore 61 and a reduced diameter bore 64 formed at the lower end of the bore 48. Adjacent the intersection of the bores 63 and 64, a conically shaped valve seat 65 is formed. The valve seat 65 is formed at the base of a larger diameter bore 66 which is, in turn, counterbored at 67. A tension screw 68 is received within the counter bore 67 and has an opening 69 that permits the flow of hydraulic fluid through this screw. The tension screw 68 engages a coil spring 71 which bears against a ball check valve 72 to urge this check valve into engagement with the seat 65.

A tube 70 has fittings 73 and 74 at its opposite ends. The fitting 73 affords a fluid connection between the interior of the tube 72 and the bore 66. The opposite end of the tube 70 is in communication with a bore 75 formed in the housing member 21 by means of the fitting 74.

The bore 75 intersects a larger diameter bore 76 formed in the housing member 21. A piston 77, which will be described in more detail as this description proceeds, is slidably supported in the bore 76. The bore 75 is intersected by a pair of bores 78 and 79. A pressure relief valve, indicated generally by the reference numeral 81 is provided in the bore 78. The pressure relief valve 81 includes a valve member 82 that coacts with a seat 83 to control the flow through the bore 78. A coil spring 84 engages the valve member 82 and urges it toward a closed position. An adjusting plug 85 is received in a threaded opening 86 formed at the outer end of the bore 78 and engages the spring 84. The adjusting plug 85 may be suitably positioned so as to adjust the preload on the spring 84 and the pressure at which the valve 81 opens. Preferably, the head of the valve member 82 that engages the seat 83 is capable of transverse movement so that good seating will be effected without necessitating extremely close fits.

When the pressure relief valve 81 is opened flow is permitted from the bore 78 through a transversely extending bore 87 into a large diameter reservoir tube 88. The reservoir tube 88 is positioned between the housing member and the pump housing 43. O-ring seals 89 are provided at opposite ends of the reservoir tube 88 to assure good sealing with the housing member 21 and pump housing 43, respectively. At the pump housing 43 the reservoir tube 88 communicates with a bore which bore, in turn, terminates at a smaller diameter

passage 90 that intersects the piston bore 48. At one extreme end of the stroke of the piston 49, the passage 90 is in communication with the bore 48. At the other positions of the piston 49, this piston blocks the communication between the passage 90 and the bore 48.

A second passage 91 intersects the bore formed at one end of the reservoir tube 88 at a considerable angle to the first passage 90. The passage 91, in turn, intersects a bore 92 that is closed by a plug. The bore 92 is also intersected by a passage 93 which intersects the bore 47. Thus, communication is provided between the reservoir tube 88 and the bore 47 via the passage 91, bore 92 and passage 93.

The passage 87 intersects the check valve 81 and has a portion 94 that extends beyond this point of intersection and which, in turn, intersects the passage 79. A release valve assembly, indicated generally by the reference numeral 95 has a valve member 96 that engages a seat 97 formed adjacent the intersection of the passage 79 with the passage 75. The valve member 96 is engaged by a stem 98 of a release knob 99 for holding the valve member 96 in position. The valve member 96 is, however, free to shift transversely relative to the stem 96 so as to seek a centralized location within the valve seat 97. As has been noted in connection with the construction of the relief valve 81, this free floating relationship permits good sealing at a low cost. The knob 99 has a threaded shank 101 that is received in a tapped opening 102 in the housing member 21.

Before proceeding to a description of the method in which the die set 18 functions, a brief description of the operation of the hydraulic pump assembly 16 and motor assembly 17 is in order. FIG. 2 of the drawings illustrates the mechanism at the completion of a stroke of the pump 16. At this point both the inner piston 49 and the outer piston 53 and the associated piston head 56 will have reached the end of their strokes. The spring 59 will also have compressed due to movement of the inner piston 49 relative to the outer piston 53, as will become apparent. In order to initiate the next pumping operation, the handle 13 is pivoted in a clockwise direction about the pivot pin 14. Because the inner piston 49 is directly coupled to the handle 13, it will be withdrawn first along the bore 48. The outer piston 53 and its associated piston head 56 will not begin a return stroke during the initial movement of the inner piston 49 and the spring 59 will be permitted to expand. When the pin 52 reaches the end of the slot 58, the outer piston 53 and its associated piston head 59 will be withdrawn along with the inner piston 49.

During this movement, the check valve 72 will preclude the return flow of fluid into the bore 48 from the passage 66. Some fluid may leak into the area of the bore 48 opened by the return of the piston 49 through the passage 90 past the piston. When the piston 49 has been withdrawn sufficiently to expose the end of the passage 93 the bore 48 will be completely filled with fluid, this fluid having come from the reservoir tube 88. The bore 47 will also be charged with fluid from the reservoir tube 88 through passage 91 bore 92 and passage 93.

When the handle 13 is again forced downwardly in a counterclockwise direction about the pivot pin 14, the inner piston 49 and outer piston 53 will move together. Even though the pin 52 is at the outer end of the slot 58, the spring 59 will transmit motion from the inner piston 49 to the outer piston 53. The piston head 58

will displace a large volume of fluid from the bore 47 to the passage 60, past the check valve 62 into the passage 61. This fluid then flows through the passage 63 past the ball valve 72 to operate the die set 18, as will become apparent. The back pressure in the reservoir tube 88 precludes flow from the bore 47 back into the reservoir tube 88. Simultaneously, the inner piston 49 will displace fluid from the bore 48 through the passage 63 past the ball valve 72 to also operate on the die set. 5 When the fluid pressure acting on the motor 17 reaches a predetermined value, as set by the preload of the spring 59 the piston head 56 will cease to displace further fluid and only the inner piston 49 will be effective for this purpose. If too high a pressure is developed, the 10 relief valve 81 will open and permit flow back into the reservoir 88. Also, when it is desired to return the die 18 to a fully opened position the release valve 95 is turned so that the pressure can act upon the release valve member 96 to open it and permit fluid to return 15 to the reservoir tube 88.

The die assembly 18 is best shown in FIG. 5 and is comprised of a first pair of dies 105 and 106 and a second pair of dies 107 and 108 (FIG. 3). The dies 105 and 106 have mating surfaces in which grooves 109 and 111 are formed. The grooves 109 and 111 are adapted to form a cavity in which a wire (not shown) is gripped when the mating faces of the dies 105 and 106 are in engagement. In like manner, the dies 107 and 108 are formed with grooves 112 and 113, respectively, for 20 forming a wire or cable receiving cavity. The dies 105 and 106 have surfaces 114 and 115 which face corresponding surfaces 116 and 117 of the dies 107 and 108. Flash receiving cavities 118 are formed in each of the 25 surfaces 114, 115, 116 and 117, for a reason which will become well apparent as this description proceeds.

The upper and lower surfaces of the die 106 are provided with intermediate angularly shaped recesses 119. The die 105 is formed with complementary shaped projections 121 that are adapted to extend into the recesses 119 to locate the die 105 with respect to the die 106 in a direction parallel to the axis of the wire that is received in the grooves 109 and 111. The construction, however, permits movement of the dies 105 and 106 30 toward and away from each other. In a like manner, the die 108 is formed with recesses 122 into which complementary extensions 123 of the die 107 extend to provide axial location of these dies relative to each other.

The dies 105 and 107 are positioned between retaining plates 124 and 125 (FIGS. 2, 5 and 6). The retaining plates 124 and 125 are clamped to flattened surfaces 126 and 127 of an extending portion 128 of the piston 77. Socket headed screws 129 and locating dowels 131 hold these elements together.

A collar 132 encircles the plates 124 and 125 and further assists in locating and retaining the plates 124 and 125 relative to the piston portion 128. The collar 132 is bored as at 133 to receive a locating dowel 134. The dowel 134 is staked into a bore 135 in the housing member projection 41. Thus, the collar is held against axial movement relative to the housing member bore 76.

The dies 106 and 108 are located between a pair of plates 136 and 137 (FIGS. 2, 5 and 7). The plates 136 and 137 are fixed to a projection 138 of a V-block member 139 by means of socket headed screws 140 and locating dowels 142. The V-block 139 has a cylin-

drical portion 141 that is received in a bore 142 of the housing member 19. A socket headed screw 143 extends through a bore 144 in an end wall of the housing member 19 and is threaded into a tapped hole 145 formed in the V-block 139 to axially affix the V-block 139 relative to the housing member 19.

The dies 105 and 107 have angularly disposed surfaces 151 and 152 (FIGS. 3 and 5) that are engaged with corresponding angularly disposed surfaces 153 and 154 of the piston extensions 128. The piston extension 128 is, in fact, a V-block for actuating the dies 105 and 107 as will become more apparent. The upper and lower surfaces of the dies 105 and 107 are formed with inclined grooves 156 and 157. Pairs of pins 158 and 159 are affixed to each of the plates 124 and 125 and extend into the grooves 156 and 157, respectively, to locate the dies 105 and 107 relative to the assembly comprised of the plates 124 and 125 and the V-block 128. This location permits the dies 105 and 106 to move in a direction parallel to their inclined surfaces 151 and 152.

A similar arrangement is provided for locating the dies 106 and 108 relative to the V-block 139 and plates 136 and 137. This arrangement includes grooves 161 formed in the upper and lower faces of the die 106 and upper and lower grooves 162 formed in the upper and lower faces of the die 108. Pairs of pins 163 and 164 are affixed to the plates 136 and 137 and engage the grooves 161 and 162 respectively. This arrangement insures that the dies 106 and 108 are located accurately but are free to move in a direction parallel to inclined surfaces 165 and 166 of the dies 106 and 108, respectively. The inclined surfaces 165 and 166 are engaged with corresponding inclined surfaces 167 and 168 of the V-block 139.

At the adjacent termination of the die surfaces 151 and 152 the dies 105 and 106 are formed with angularly disposed surfaces 171 and 172. The angularly disposed surfaces 171 and 172 are engaged by corresponding surfaces 173 and 174 (FIG. 3) of a plunger 175. The plunger 175 is slidably supported within a counterbored passage 176 of the piston 77. A coil spring 177 bears against the plunger 175 and is loaded by an adjusting plug 178 received in a threaded opening 179 of the piston 77 to normally urge the plunger 175 to an extended position as shown in the Figures. A second plug 181 closes the outer end of the counterbore 179 and precludes the leakage of hydraulic fluid from the housing bore 76 and the piston 77.

The dies 106 and 107 also have inclined surfaces 182 and 183 that are engaged by inclined surfaces 184 and 185 of a second plunger 186. The plunger 186 is slidably supported in a counterbored opening 187 formed in the V-block 139. A coil spring 188 bears against the second plunger 186 and against a plug 189 that is threaded into the V-block 139. The spring 188 urges the plunger 186 toward a fully extended position.

A coil spring 191 encircles the piston 77 (FIG. 2). The coil spring 191 is located between the collar 132 and a shoulder 192 formed at the upper end of the piston 77. The spring 191 normally urges the piston 77 to an extreme righthand position until a pair of flanges 193 and 194 of the plates 124 and 125 engage the collar 132. The spring 191 exerts a force tending to oppose any hydraulic pressure in the bore 76. A sealing ring 195 is received in a groove 196 in the piston 77 to effect sealing of the bore 76.

A gripping assembly, best shown in FIGS. 1 and 4, is provided for holding the ends of the wires to cables to be welded during the welding sequence, as will become apparent. This assembly includes a gripping finger housing, indicated generally by the reference numeral 201. The housing 201 has a cylindrical bore 202 that is slidably supported upon a cylindrical portion 203 of the housing member 19. At each side of the housing member 19, the finger housing has lugs 204 and 205 each of which have respective bores, only one of which appears at 206. A cylindrical shank 207 of respective gripping fingers 208, 209, 211 and 212 is journaled for pivotal movement in each bore 206.

The gripping fingers 208 and 209 have depending pin projections 213 and 214 that are received in a transversely extending groove 215 of a generally L-shaped release finger 216. The release finger 216 is slidably supported in a groove 217 formed in the lug 204 of the finger housing member 201. A corresponding arrangement is provided for the gripping fingers 211 and 212. For this reason, the structure associated with these fingers will not be described in detail and has been identified by the same reference numerals. A coil spring 220 is received in a bore 218 at the base of each lug and engages the release fingers 216 to urge them in an outward direction. The degree of movement in this direction is limited by the contact of one of the gripping finger with pin 219.

The entire gripping finger arrangement including the housing member 201 is, as has been noted, slidably supported on the housing member 19. A return spring 221 of a flat annular shape is affixed at its center to the housing member 19 by means of a bolt 222 and washer 223. The spring 221 is slotted in a generally radial direction and these fingers engage a shoulder 224 formed on the end of the finger housing member 201.

OPERATION

The drawings illustrate the mechanism with the dies 105, 106, 107 and 108 in a retracted position. In this position, the ends of wires or cables to be welded are inserted into the cavities defined by the grooves 109 and 111 and 112 and 113, respectively. This is accomplished by applying a pressure to the release fingers 216 so as to pivot the gripping fingers 208, 209, 211 and 212 in an opening direction. The wire ends are slid into abutment at the point of juncture of the mating faces of the dies 105 and 106 with the dies 107 and 108. At this time, the release fingers 216 are released and the gripping fingers 208, 209, 211 and 212 will grasp and retain the wire ends.

The release valve 95 is then moved to its closed position as shown in the Figures and the handle 13 is operated. As has been previously noted, pivotal movement of the handle assembly 13 causes both the inner piston 49 and the outer piston head 56 to displace fluid past the ball valve 72 into the bore 76. During the initial phase of movement, the effect of the piston head 56 causes the primary displacement of fluid. Because this piston head has the larger effective area, the fluid is displaced at a greater volume but lower pressure than that provided by the inner piston 49. This pressure acts upon the piston 77 in opposition to the spring 191 and causes the V-block portion 128 of the piston to approach the V-block 138. As the V-blocks move together, the inclined surfaces of these V-blocks act upon the corresponding inclined surfaces of the dies 105,

106, 107 and 108 to exert a pressure on these dies. Initially, the plungers 175 and 186 will prevent the dies 105 and 106 from moving toward the dies 107 and 108. The springs 177 and 188 exert more pressure than the initial force exerted on the motor 17. Thus, the pairs of dies 105, 106 and 107, 108, will be initially forced toward each other until their cooperating faces are in abutment. At this time, the respective ends of the wires will be gripped in their grooves.

The initial closure of the dies 105, 106 and 107, 108 is accomplished at a very high rate of movement but with a relatively small force transmission due to the aforesaid effect of the piston head 56. Once the dies 105, 106 and 107, 108 are in engagement, a greater pressure is required to support further movement. The piston head 56 will not be capable of generating this higher pressure and the spring 59 will yield so that only the inner piston 49 is effective to displace fluid into the bore 76. The piston 49 provides an extremely high pressure due to its small area.

Upon continued pumping action of the handle assembly 13, sufficient pressure will be exerted on the piston 77 to overcome the action of the springs 177 and 188 and the pairs of closed dies 105, 106, and 107, 108 will be urged toward each other. Since the wire has been gripped in these dies an upset of the ends of the wires will occur, as is well known in this art. The flash from the upset metal will be displaced in the die cavities 118.

The relief valve assembly 81 will remain in its closed position until the preset pressure is developed in the cylinder 76. At that time, the valve 81 will open so that further pumping of the piston 49 will merely transfer fluid back to the reservoir tube 88. Thus, the force exerted by the fluid motor 17 on the dies 105, 106, 107 and 108 and upon the wires gripped thereby will be limited by the pressure at which the valve 81 is set to open.

The gripping fingers 208, 209, 211 and 212 permit the wire ends to slide in an inward direction during the aforesaid procedure. It will be noted that the centers of the die cavities defined by the grooves 109, 111 and 112 and 113 move axially relative to the handle assembly. During this axial movement the entire gripping assembly slides against the action of the spring 221.

After the dies have moved completely together to finish an initial upset, the release valve 95 is opened to relieve the hydraulic pressure in the chamber 76. The spring 191 will then urge the piston 77 to its initial position and the plungers 175 and 186 will cause the dies to retract. When the dies 105, 106, 107 and 108 are retracted, the gripping fingers 208, 209, 211 and 212 will hold the joined ends of the wires against retraction along with the dies. Thus, no tensile load will be placed upon the joined wire ends. Successive upsets are then made in the manner previously described until a good weld has been provided. At that time, the latch 32 is released and the housing member 19 is pivoted to an opened position so that the welded wire ends may be removed. In addition, this opening of the housing assembly permits removal of any flash from between the die faces and permits inspection of the dies surfaces. Furthermore, if desired the dies may be conveniently removed at this time.

It should be readily apparent that the description construction may be conveniently hand held and hand operated due to the hydraulic force amplification. The

pump 16 is, in effect, a variable rate pump due to the action of the inner piston 49 and the outer piston 53 and its association piston head 56. Initial operation of the pump displaces large volumes of fluid at a low pressure. This effects rapid closure of the dies without necessitating operation of the handle 13. The final movement of the dies is, however, accomplished at a very high pressure due to the amplification provided for by the small inner piston 49. The dies may be conveniently removed and inspected and an extremely compact

10 overall assembly is provided. Furthermore, the arrangement limits the force that is applied to the welding dies and to the welded workpieces. Such an arrangement also would have utility in mechanically operated machines and it is deemed within the purview of this invention to provide a corresponding structure for limiting the force applied in machines having purely mechanical die actuating arrangements.

In some instances it may be desirable to arrange the components in a different configuration. That is, it may be desirable to have the dies and their supporting housing assemblies extended at an angle to the reservoir portion of the handle mechanism. Such an arrangement may prove more satisfactory for certain applications. Such changes may be made without departing from the spirit and scope of the invention as defined by the appended claims.

25 We claim:

1. In a cold welding apparatus comprising die means movable between an opened position and a welding position for upsetting a work piece and operating means including a manually operable two stage hydraulic

30 pump for moving said die means between its opened position and its welding position, said pump being operable in its first stage for displacing a first volume of fluid at a first pressure for effecting initial movement of said die means from its opened position to its welding position at a first rate of speed said two stage pump being effective in its second stage to displace a second volume of fluid at a second pressure, said second volume being less than said first volume and said second pressure being greater than said first pressure for effecting movement of said die means to its welding position at a second rate of speed slower than said first rate of speed, said pump being operable from its first stage to its second stage as said die means approaches its welding position.

2. A cold welding apparatus as set forth in claim 1 45 wherein the die means comprises a first pair of dies and a second pair of dies, said dies of said pairs being movable relative to each other between an opened position and a closed position, said pairs of dies being movable relative to each other between an opened position and a welding position.

3. A cold welding apparatus as set forth in claim 1 50 wherein the two stage hydraulic pump is comprised of a first piston having a relatively first effective area and a second piston having a relatively second effective area, said second area being greater than said first area.

4. A cold welding apparatus as set forth in claim 3 55 wherein the die means comprises a first pair of dies and a second pair of dies, said dies of said pairs being movable relative to each other between an opened position and a closed position, said pairs of dies being movable relative to each other between an opened position and a welding position.

5. A cold welding apparatus as set forth in claim 1 60 further including an operating handle wherein the first piston is directly coupled to the operating handle and the second piston is coupled to the operating handle by means including a lost motion connection and spring means.
